UNITED STATES PATENT OFFICE.

MARTIN FADER, OF BAYSIDE, CANADA.

FOOD-CUTTER.

SPECIFICATION forming part of Letters Patent No. 443,754, dated December 30, 1890.

Application filed July 22, 1890. Serial No. 359,550. (No model.)

To all whom it may concern:

Be it known that I, MARTIN FADER, of Bayside, in the county of Halifax and Province of Nova Scotia, Canada, have invented certain new and useful Improvements in Food-Cutters; and I do hereby declare that the following is a full, clear, and exact description thereof, reference being had to the accompanying drawings.

10 My invention relates to mechanism for the cutting of food, principally bread and meat. It may also be employed in the cutting of bait for the use of fishermen on the coast.

In the drawings, Figure 1 is a central longitudinal section through Fig. 3, looking in the direction of arrow 1. Fig. 2 is a sectional plan view taken through the line X X on Fig. 1. Fig. 3 is a sectional elevation taken through the line Y Y on Fig. 1. Fig. 4 is a 20 sectional detail taken through the line Z Z on Fig. 1. Fig. 5 is a detail view of the gage. Fig. 6 is a sectional detail view of the gage and part of the side boards of the machine.

a a, &c., are the legs of the machine. b is a 25 table resting upon said legs. c c are side boards placed upon two of the edges of said table. d d d d are uprights let into the outside surface of said side boards, so as to constitute vertical ways or guides for the frame 30 of a cross-knife e. This cross-knife is inserted by means of rivets into a frame composed of two pieces f f', which frame moves up and down between said guides d d d d. The frame is connected by vertical rods g g' to the top 35 bar h. The lower ends of the rods g g' are connected by pitmen h' h' to a treadle i. This treadle has a spring j, so that after the foot of the operator brings down the treadle and thereby the knife between the side boards 40 c c, in order to cut any substance placed under-

neath the knife, upon releasing the foot the knife will rise up between the ways d d d d. The upper ends of the pitmen h' h' are connected to the lower ends of the rods g g' by means of set-screws k k.

45 l is a gage-board, which has flanges l' l'. These flanges move in grooves m m, &c., made upon the inner surfaces of the side boards c c. The flanges l' l' are placed upon the ends of the gage-board l nearer one surface than the other, so that by reversing the gage-board—in other words, presenting the opposite surface of the gage-board to the cutting-knife—a different thickness of cut will be obtained on the substance operated upon.

50 n is a feeder-board with a handle o placed between the side boards c c, being connected by sides n' n'. Such feeder-board aids merely in pushing up the loaf of bread, piece of meat, bait for fish, or other article of food to the cutter, to be operated upon.

55 p is a slot in the table b, through which the slices or pieces cut may pass into a drawer q. The drawer q moves in ways r r underneath the table and is pulled out and pushed in by 60 means of the handle s. I prefer to make the bottom of the drawer sloping, as shown at t.

I claim—

65 In a food-cutter, the combination of a knife moving in ways with a gage-board formed with flanges and having a varying thickness of the board upon opposite sides of these flanges, the side boards of the cutter containing vertical grooves upon their inner sides for the reception of the flanges of the gage-board, substantially as described.

70 MARTIN FADER.
